UNITED STATES PATENT OFFICE.

HUGH BAINES, OF BROOKLYN, NEW YORK.

VELOCIPED.

SPECIFICATION forming part of Letters Patent No. 390,641, dated October 9, 1888.

Application filed December 15, 1887. Serial No. 237,988. (No model.)

To all whom it may concern:

Be it known that I, HUGH BAINES, a subject of the Queen of Great Britain, residing at Brooklyn, county of Kings, and State of New York, have invented certain new and useful Improvements in Vehicles or Motors, and in the mode of controlling the same, of which the following is a full, clear, and exact specification.

10 My invention relates, broadly, to mechanism to be employed in conjunction with any source of power for communicating the power from said source to the point or to the mechanism or apparatus by which the said power is utilized, and to an apparatus for controlling the direction of the traverse of the same; but for convenience of illustration I have shown my improvements as applied to a road-vehicle, as it appears to be most applicable to 15 this class of devices, and it is designed as an improvement over the methods of propulsion and steering as shown in patents granted to me in the United States, dated January 26, 1886, No. 334,839, and October 19, 1885, Nos. 351,150 and 351,243; in Great Britain, dated May 12, 20 1885, and numbered 5,827; in France, dated May 12, 1885, and numbered 168,887; in Germany, dated May 12, 1885, and numbered 34,432; in Belgium, dated May 12, 1885, and numbered 68,847; in Italy, dated May 15, 25 1885, and numbered 18,346, and in Canada, dated June 9, 1885, and numbered 41,488.

30 My invention has for its object, when used in connection with a vehicle for the propulsion and guidance of the same, to accomplish the result sought to be attained in the inventions covered by my patents above referred to; but my present invention accomplishes the object sought by a much more effective, economical, and less complicated means.

35 It is a well-conceded fact that in the propulsion of all vehicles, vessels, and like devices, and in fact in the operation of any mechanism, the inertia when the power is first applied offers so much resistance to the motor that its power is reduced to a considerable extent, and thus causes, comparatively speaking, a great loss of time in getting the vehicle or vessel under way or the mechanism into operation. 40 Therefore my object is to overcome this difficulty in a further degree than has yet been attained, which I do by increasing the leverage

of the operating-lever at the beginning of the stroke or at the moment of the application of the power, and gradually decreasing it as the throw is completed, so that in the long run the length of the stroke varies but slightly from the length of the stroke of an ordinary lever of the same length. As this feature of the invention will doubtless be most appreciated by 55 those who ride vehicles which are propelled by foot or hand, I deem it most expedient for the sake of illustration and a thorough understanding of the principle of the invention to show it as applied to a tricycle for the propulsion of the same.

50 A further object of my invention is to avoid loss of motion in transmitting the power from the initial point of application to the wheels, and also to avoid the side pull or wabbling of 70 the vehicle caused by the power being applied to the wheel alternately, all as will be hereinafter fully explained.

55 In the accompanying drawings, which form an important part of this application, Figure 75 1 represents a tricycle in side elevation having my improvements applied thereto for transmitting power from the feet of the rider to the driving-wheels. Fig. 2 is a plan view of the same. Fig. 3 is a vertical longitudinal section 80 taken on the line X X, Fig. 2. Fig. 4 is a detailed perspective view. Fig. 5 is a detached view of the preferred form of my improved motor. Fig. 6 is a modified form of the same, and Fig. 7 is still another form of modification.

65 In utilizing the invention in the propulsion and guidance of a tricycle I bridge the upper part of the frame 1 with a brace or bracket, 2, which is secured at each end to the said frame 90 by bolts or other suitable means. Near the middle of this brace and on the under side are two curved downwardly-projecting hangers, 3 4, having extending between their lower ends a pintle or shaft, 5, which passes through the 95 central brace-bar, 6, which passes midway between the hangers 3 4 and rests loosely upon the sill 7, extending athwart the lower portion of main frame; but the said bar 6 is held against too great displacement by means of a 100 link, 8. On both sides of the brace-bar 6, journaled on the pintle 5, is a sector, 9, which is provided in its periphery with a groove and in the center of the curve which its pe-

riphery forms, but to one side of the said groove, with an ear, 10. Pivoted to this ear is the treadle or operating-lever 11, and pivoted to the upper part of the hangers 3 4 is a swinging lever, 12. These levers are of such length that their converging ends will meet, and their meeting ends are provided with rounded or cammed faces, in which teeth are cut and adapted to interlock or mesh with each other.

10 The cam or curve is so formed as to admit of but the first teeth, as at 13, engaging while the treadle or operating-lever 11 is in its normally-elevated position, and it will be observed that the distance between the point of contact 15 of said teeth and the point at which the lever 11 is pivoted to the ear 10 determines the length of the leverage; hence while the operating-lever is in its normal position ready to receive the pressure from the foot the lever-20 age is very long compared with the length between the point of contact of the teeth and the point of fulcrum, thus affording very great power at the commencement of the stroke for overcoming the inertia of the machine; but as 25 the stroke advances the curved or cam surfaces will roll together, the lever 12 will swing toward the cam-face of the lever 11, the nose or toe 14 of the former lever will gradually swing downwardly in an arc and hold the 30 nose 15 of the latter lever depressed, and thus gradually decrease the distance between the fulcrum and the point at which the teeth contact, and at the same time decrease the throw of the operating-lever 11.

35 It will of course be understood that great leverage is only essential at the time of application of the power, and that the momentum, when once gained, can be easily perpetuated by a lever of considerably less throw. I trans-40 mit the power to the traction-wheels 17 of the vehicle by the following means:

Secured at 13 to the lower side of the sectors 9, which move downwardly in an arc, are cables 19, which are also secured to the grooved 45 wheels 20, and around which latter the cables are partly rove. Each of these wheels is made integral with or secured to an independent tooth-carrier, 21, which is journaled loosely on the axle of the vehicle upon each side of 50 the central brace, 6, and to afford a small bearing-surface for these carriers I form them so they will be adapted to contact with the axle at each end only, as shown in Fig. 3. Each of these carriers carries at its outer end 55 a bracket, 22, which extends upwardly and across the clip 23, by which the frame is swung from the axle, so as to bring the pivoted teeth 24 25 26 over the ratchet 27, which latter is made integral with the hub of the traction-60 wheel. These teeth are mounted upon a journal, 28, which extends across this bracket 23 and is riveted therein, and they vary in length, the shortest one being barely long enough to rest upon the outer edge of the ratchet-tooth 65 while the longest is bearing in the notch formed by the tooth just passed, so that by the slightest movement of the carrier one tooth

will immediately be caused to engage a notch, and thus avoid any lost motion. When the carrier is revolved forward, the tooth will engage the ratchet of the hub and cause the vehicle to move forward, and when the power is released from the treadle the weight 29, secured to each of the teeth-carriers, will cause the teeth to retrograde, and also the cables to 75 rewind upon the wheels 20.

In order to remedy the wobbling motion of the machine produced by the side pull before referred to, I provide each of the grooved pulleys with an arm, 50, which may be secured 80 to or made integral with said pulleys, and projects upwardly and across to the farther end of the opposite carriers. Connected to the extremity of each of these arms by means of a cord or cable, 51, is a spring, 52, which 85 latter is also connected to the frame of the vehicle. It may be here stated that the wheels may make one-fourth or more of a revolution at each stroke of the treadle, and that these arms 50 are arranged so as to remain normally 90 at a distance apart equal to about one-fourth the circumference of the grooved pulley 20, in order that each of said arms may move forward one-quarter revolution without interfering with each other, the arms of course passing outside of the weights 29. By this arrangement it will be seen that when the power is applied to the tooth-carriers, and consequently to one traction-wheel, the overhanging arm 50 will draw upon the spring on the 100 opposite side of the frame and pull this side forward against the axle, and consequently distribute the power equally in the frame of the vehicle. These springs 52 will also assist the weights 29 in returning the carrier to its 105 normal position.

The mechanism for steering the vehicle consists of a worm-wheel, 30, which is keyed to the head of the forks of the steering-wheel, and with which wheel 30 engages a worm, 31, 110 which latter is journaled in the brackets 32 and is provided at each end with a grooved pulley, 33. Secured to each of these pulleys, but on opposite sides thereof, is a rein, 34, which passes under a roller, 35, mounted in 115 the brackets 36, and terminates within convenient reach of the rider. The advantage of this arrangement is that the machine is guided by pulling upon the rein in the direction that it is desired to travel, and not vice versa, as 120 heretofore.

37 are brake-shoes, which are mounted on the rod 38 and are brought to bear by the bell-crank lever 39, mounted in the bracket 40, and having a step on one of its arms and the other 125 of its arms connected with the rod 38 by means of a link, 41, which link passes through an opening in a boss on the under side of the brace or bracket 2, and thus supports the brake-shoes and the rod to which they are secured.

In order to support the center of the axle and prevent sagging, I form the central brace-bar, 6, with an upwardly-projecting rod, 53,

which is secured to a cross-bar at the top of the main frame, the arms 50 being notched so as not to come in contact with said bar.

In adapting the vehicle for travel over frosty 5 and snowy roads, I provide the tires of the traction-wheels with ice-creepers, and I mount the steering-wheel upon skids or runners, all as shown in dotted lines.

The form of "treadle" mechanism, as I term 10 it, which I have just described, is very applicable to this purpose; but the preferred form is shown in Fig. 5 of the drawings. This latter form is identical with the other, with the exception that the nose of the cam of the operating-lever 11 is provided with an elongation, 42, which is bifurcated at its extremity, and has a roller, 43, mounted therein and above this roller; but a little below the pivot of the sector 9 is a track, 44, for said roller to 15 bear and roll against, and which track may be securely fastened to any stationary or convenient part of the vehicle or motor with which the apparatus is to be used. Now in this instance it will be seen that when the operating-lever 11 is in its normal elevated position the roller 43 is out of engagement with the said track, and the teeth of the two levers nearest to the point of fulcrum of the lever 11 are in engagement; but as the throw of the lever 20 25 progresses the roller will come in contact with the track 44, prevent the end of the lever from rising higher, and immediately disengage the toothed faces of the cams, and at the same time increase the length of the lever 30 between the fulcrum and roller, and consequently cut off the length of the leverage 11. Thus I have the greatest leverage to start with, with a decrease of leverage and a consequent decrease of stroke to end with.

40 In the modification shown in Fig. 6 I have done away with the swinging lever 11 and the toothed cam-surfaces, and I have employed a plain operating-lever, 45, without the roller 43, and instead of a plain track, as in the previous form, I employ two rollers, 46 47, which perform the same function as the track 44. It will be seen that in this instance the result is substantially the same as that attained by the previous forms. When the stroke of the lever 45 is begun, its end will bear up against the roller 46, which is very near the point of fulcrum; but as the stroke advances the end of the lever will leave the roller 46 and come in contact with the roller 47, thus practically 50 changing the position of the fulcrum, and consequently decreasing the throw of the lever.

In still another modification I employ merely a sector pivoted at the point 48, with an arm or lever, 49, projecting from its periphery. 55 This form I use when simplicity and cheapness are essential.

Having thus described my invention, the following is what I claim as new therein and desire to secure by Letters Patent:

60 1. In a vehicle or motor, the combination, with the driving drum or pulley 20, of a pivoted sector, a cord or cable connecting said

drum or pulley with said sector, an operating-lever pivoted to said sector and having a beveled or rounded end, and a swinging lever having a beveled or rounded end for engaging said bevel of the operating-lever, substantially as set forth. 70

2. In an operating mechanism for a vehicle or motor, the combination, with a pivoted 75 sector, of a table or track below the pivot of said sector, and an operating-lever fulcrumed to said sector and adapted to engage said track with its end, substantially as set forth.

3. In an operating mechanism for a vehicle or motor, the combination, with a pivoted 80 sector, of a track arranged below the pivot of said sector, an operating-lever fulcrumed to said sector, a cam or rounded surface on said lever with teeth formed therein, an elongation 85 on said lever beyond its teeth, a roller mounted on said elongation and adapted to engage said track, and a swinging lever having teeth adapted to engage the teeth of the aforesaid lever, substantially as set forth. 90

4. In a vehicle, substantially as described, the combination, with the axle and main frame, of the central brace-bar, 6, resting upon the sill 7 and secured to the axle, and having an upwardly-projecting suspension-rod secured 95 to the main frame, substantially as set forth.

5. In a steering apparatus, the combination, with the forks of the guide-wheel and a worm-wheel keyed in a horizontal plane thereto, of the brackets 32, a worm mounted horizontally 100 in said brackets and engaging said worm-wheel, a pulley or drum on each end of said worm, and reins secured to said drums on opposite sides, whereby the vehicle will be steered toward the rein that is pulled and the other rein 105 will be wound upon its drum, substantially as set forth.

6. The combination, with the drums on the axle, having means for engaging the driving-wheels, of the bar 2, having hangers thereon, 110 sectors journaled between said hangers, cords or cables connecting said drums and sectors, operating-levers pivoted to said sectors and having rounded or beveled ends with teeth formed thereon, swing-levers having similarly-formed 115 ends, and the teeth on said swing and operating levers being adapted to mesh or interlock, substantially as set forth.

7. The combination, with the operating lever or levers and the axle having the traction-wheels thereon, of a carrier or carriers on said axle, a ratchet on each of said wheels, two or more teeth of graduated lengths pivoted to said carriers, and a cable or cables wound on each of said carriers and connected with the 125 operating-levers, substantially as set forth.

8. The combination, with the carrier, a bracket, 25, on the end of said carrier, the journal 28, extending across said bracket, and two or more teeth of graduated lengths mounted on said journal, of the ratchet on the hub of the driving-wheel and suitable means for rotating said carriers, substantially as set forth. 130

9. The combination, with the driving-wheels

- journaled upon the axle and the main frame, of the carriers surrounding said axle, ratchets on said wheels, brackets on said carriers, two or more pivoted teeth of different lengths 5 mounted in said brackets and adapted to engage said ratchets and projecting from each of said carriers to the opposite end of the axle, and springs connected with said arms and main frame, substantially as set forth.
10. In an apparatus for propelling a vehicle or motor, the combination, with the vehicle-frame and the axle having the traction-wheels thereon, of a sector pivoted in said frame be-

low the axle, an operating lever attached to and projecting from said sector, a treadle on 15 said lever, a carrier on said axle provided with teeth or their equivalents, as shown and described, a ratchet on the hub of the traction-wheel adapted to be engaged by said teeth, and a cable wound upon said carrier and connected with said sector, substantially as shown and described.

HUGH BAINES.
